UNITED STATES PATENT OFFICE.

OLE SKAAR, OF AKRON, OHIO.

BOX OPENER.

Application filed September 3, 1921. Serial No. 498,283.

To all whom it may concern:

Be it known that I, OLE SKAAR, citizen of the United States, residing at Akron, in the county of Summit and State of Ohio, 5 have invented certain new and useful Improvements in Box Openers, of which the following is a specification.

This invention relates to a box opener, and has for its object the production of a simple 10 and efficient means, which may be attached to the lid of a box, and permit the lid to be opened by pressing upon the opening means.

Another object of the invention is the production of a box opening means which consists of a minimum number of parts, and which may be cheaply manufactured. 15

Other objects of the present invention will appear throughout the following specification and claim.

20 In the drawings:

Figure 1 is a side elevation of a box, partly in section.

Figure 2 is a front elevation of the opening means attached to the box.

25 Figure 3 is a top plan view of a portion of the box, the opening means being attached thereto.

By referring to the drawings it will be seen that 1 designates the body of the box, such as a shoe blacking or salve box of the ordinary construction. A rib 2 is formed around the lower end of the box, as shown in Figure 1, and is adapted to be engaged by the lower end of the opening spring 3.

30 The spring 3 is fixedly secured to the top 4 of the box by means of a rivet 5, which passes through the overhanging end 6 of the opening spring 3. The spring 3 is bowed outwardly between its ends, so that the respective ends of the spring 3 will engage the bottom and top of the box, as shown clearly 35 in Figure 1 of the drawing.

When it is desired to open the box, the operator will place his thumb against the spring 3 and force the spring inwardly, thereby 45 forcing the top of the box upwardly with respect to the body of the box, thereby permitting the lid or cover 4 to be easily removed from the body of the box. By having the spring 3 secured to the top 4 and engaging 50 the rib 2 at its lower end, it will be seen that the top will be easily raised when pressure is brought against the spring 3 intermediate the ends thereof.

Having fully described the invention, 55 what is claimed is:

In combination with a box including a body having a rib formed thereon and a cover for the body, a device for facilitating the removal of the cover from the body including an arcuate spring body adapted to extend the entire height of the box, and an inwardly extending straight attaching ear arranged to overlie the top of the cover and to lie flat thereon and terminate outwardly 60 of the center of the cover, the free lower end of the arcuate spring body engaging the rib when the cover is on the body, and means disposed adjacent to the edge of the top 65 wall of the cover and extending through the top wall and the attaching ear for normally holding the device in position on the cover, the meeting portion of the arcuate resilient body and the attaching ear engaging the cover at all times, whereby swinging movement of the resilient body is prevented in relation to the cover and rib. 70

75 In testimony whereof he affixes his signature in presence of two witnesses.

OLE SKAAR.
